(57) **CLAIM**

I claim the ornamental design for a one-piece molded wainscot system, as shown and described.

DESCRIPTION

FIG. 1 is a fragmentary front view of a one-piece molded wainscot system showing my design;

FIG. 2 is a cross-sectional view of the broken lower mid-section of the wainscot system of FIG. 1;

FIG. 3 is an enlarged fragmentary side elevational view of the wainscot system of FIG. 1 from one side of the wainscot system, the other side being identical to the side shown; and, FIG. 4 is an enlarged top plan view of the one-piece molded wainscot system of FIG. 1.

The back of the one-piece molded wainscot system is flat and unadorned and does not form a part of the claimed design.

The claimed design is broken on one end and in the center to indicate indeterminate length and width thereof.
